UNITED STATES PATENT OFFICE.

ALONZO G. KINYON, OF CHICAGO, ILLINOIS, ASSIGNOR TO FULLER ENGINEERING COMPANY, OF ALLENTOWN, PENNSYLVANIA.

PROCESS AND APPARATUS FOR BURNING POWDERED COAL.

Application filed May 13, 1918. Serial No. 234,055.

To all whom it may concern:

Be it known that I, ALONZO G. KINYON, a citizen of the United States, residing at Chicago, in the county of Cook and State 5 of Illinois, have invented certain new and useful Improvements in Processes and Apparatus for Burning Powdered Coal, of which the following is a specification.

My invention relates to burning powdered coal, and other kinds of powdered or fluid fuels.

One of the objects of my invention is to provide a simple and efficient process for thoroughly and intimately mixing fuel in 15 very fine particles with air in a manner to obtain maximum heat from the burning of such fuel.

A further object is the provision of a simple and efficient mechanism for intimately mixing the fuel and air and presenting them to be burned in a manner to effect maximum heat from such fuel, and without smoke.

A further object is the provision of a mechanism of the character mentioned which is substantially automatic in its operation.

A still further object is the provision of a mechanism adapted to present the fuel 30 at substantially constant speed, in a thin curtain or stream into a stream of air, and means for breaking up the air into very fine jets in order to intimately mix the air and fuel upon their coming together.

Other objects will appear hereinafter.

An embodiment of my invention is shown in the accompanying drawings, forming a part of this specification, and in which—

Fig. 1 is a side elevation of a device embodying my invention shown as applied to a furnace, the latter being shown in vertical section with the housing 74 removed.

Fig. 2 is a rear elevation of my device showing portions broken away to expose underlying parts.

Fig. 3 is an enlarged detail of a feeding roller and agitator with their connecting operating mechanism.

Fig. 4 is an enlarged fragmental section taken on line 4-4 of Fig. 2.

Figure 4⁴ is a detail plan view showing the relation of the pawl shaft, flange and ratchet wheels illustrated in Figures 2 and 4.

Fig. 5 is a view looking at the top of 55 the barrel or container for fuel.

Fig. 6 is an enlarged view looking downwardly on a part of the air passage and through the feeding roll of my device.

Fig. 7 is an enlarged broken view taken longitudinally through my feed roller.

Fig. 8 is a view taken as on line 8-8 in Fig. 6; and

Figs. 9 and 10 are sections taken on lines 9-9 and 10-10, respectively, of Fig. 7.

Referring more particularly to the drawings it will be apparent that my device is particularly adaptable for burning coal in powdered form. It will be apparent, however, that fuel in liquid or gaseous form, such as the hydro-carbons are ordinarily found in, may be employed in connection with my invention. When using a powdered fuel, such as powdered coal, such fuel is preferably provided in suitable containers, such as a barrel 11. It is preferable to provide some kind of container which can be made tight so as to prevent the loss of fuel, absorption of moisture, and also to prevent dust and dirt around the device.

In the drawings, I have indicated a boiler 80 12, which has a fire-box 13, a grate 14, and an opening 15 for the insertion of fuel into the fire-box. The parts 12, 13, 14 and 15 may be of any conventional or preferred construction, as my device is adaptable for 85 application to furnaces or boilers now in use, or may be applied to new constructions.

When installing my device, in the fire-box 13 I preferably cover the grates 14 with a refractory material 16, such as fire-brick, or 90 the like, in a manner to completely seal such grates and prevent air from entering the fire-box through the grates. The top surface of the fire-brick 16 is preferably inclined, as indicated, so that molten slag 95 which will be made in burning most coals, will not run into the burner. Above the fire-brick 16, I provide a wall 17 of fire-brick or refractory material, which is preferably disposed in relation to the wall 16, 100 so that the space between the walls 16 and 17 is gradually increased away from the burner. In front of the walls 16 and 17 I preferably provide an upright wall 18 also of fire-brick, or other refractory material, 105 against the inner side of the fire-box 13. This wall 18 is disposed at an angle somewhat near 90 degrees to the walls 16 and 17, and a wall 19 is extended upwardly away from the wall 18 so as to conduct the burn- 110

2
ing fuel upwardly and toward the front of the fire-box again. The wall 19 is preferably of fire-brick, or other refractory material, so as to withstand the heat of the burning fuel. The walls 16, 17 and 18 are all designed to catch the molten slag which is formed during the burning of most all coal and conduct such slag into a point 20 in the fire-box so that it can be easily collected and removed, and so that such slag will not enter the flues or tubes 21 of the boiler. The walls 16, 17, 18 and 19 also have the effect of retarding the heat caused by the burning fuel, permitting such heat to be radiated to the boiler. The fuel opening 15 of the fire-box 13 is partially taken up by the walls 16 and 17, and a wall 22. The wall 22 is preferably stopped a short distance below the top of the opening 15 and a door 23 fitted in such upper part of the opening 15 so that access can be had to the interior of the fire-box, when so desired. The lateral edges of the walls 16, 17, 18 and 19 are connected by means of vertical walls 24, one of which is shown in Fig. 1. The walls 24 are preferably disposed to one another so that the distances between them will be gradually increased from the point 25, where the fuel begins to burn, to the discharge opening 26, or in other words the walls encloses a chamber which increases gradually in size from one end to the other and is bent back upon itself.

An important feature of my invention is providing the burning opening 25 in a comparatively narrow and wide opening so that a thin flame will provide quick burning of the fuel, and consequently maximum heat.

The fuel is preferably delivered to the device in a container such as barrel 11, and the barrel is provided with trunnions 27, one at each side. The trunnions 27 are adapted to be engaged by sockets in the ends of two arms 28 which are formed on sector gears 29, and the latter mounted on a shaft 30. The arms 28 are preferably sufficiently flexible to permit lateral springing thereof to permit the trunnions 27 to engage the sockets in the ends of said arms, and sufficiently rigid to prevent the dislocation of the trunnions 27 during the hoisting of the barrel 11. The gears 29 are preferably operated by pinions 31, one for each gear, mounted on the ends of a shaft 32, and the latter operated by a manually operable crank 33. A pawl 31' is provided to engage the gear 31 so as to hold the barrel 11 in any desired position between those indicated by full and dotted lines in Fig. 1.

60. The barrel 11 is provided with a plane top, see Fig. 5, when in shipment and storage, but when brought to the position shown by full lines in Fig. 1, such plane top is removed and a special top inserted 65 in its place. This special top comprises an

annular member 34, having a flange 35 which rests against a flange 36 on the barrel 11. The flange 36 is preferably recessed and has an annular gasket 37 compressed between the flanges 35 and 36 to provide a tight joint between such flanges. The flanges 35 and 36 are held together by a split annular clamp 38. The parts of the clamp 38 are preferably hinged together as at 39 and provided with lugs 40 and 41. 70 To the lug 41 is connected a link 42 which is adapted to engage a point 43 on the lug 40 so that upon swinging the link 42 into engagement with the point 43 of the lug 40, the clamp 38 may be tightly drawn against the flanges 35 and 36 to secure said flanges tightly together. The member 34 is provided with a cylindrical flange 44 on which is ordinarily mounted an annular member 45, and between the flange and the annular member 45 is an annular gasket 46 which makes a tight joint between the members 44 and 45. When the barrel is brought to the position shown in dotted lines in Fig. 1, the members 45 and 46 are adapted to slide 80 downwardly onto an annular flange 47 formed at the top of a hopper 48 which is adapted to conduct the fuel into the feeding apparatus of my invention.

In the member 34 are pivoted two doors 95 or valves 49, pivoted as at 50 to suitable portions of the member 34 and adapted to swing downwardly when the parts are in the positions shown in Fig. 2. The doors 49 are held from falling down by means of cables 100 51 connected thereto and wound on a shaft 52. The shaft 52, see Fig. 4, has its ends journaled in the annular flange 44, and one end 53 squared for the engagement of a wrench, not shown, for operating the shaft 105 52. At one end of the shaft 52 I mount a ratchet wheel 54 which is engaged by a spring-pressed pawl 55 to hold the shaft 52 against rotation under the weight of fuel on the doors 49 when in the position of Fig. 2. The pawl 55 is provided with a stud or shaft 56 which extends out into the flange 44 for operation by a wrench, such as the wrench used in operating shaft 52, neither of which wrenches are shown, as any ordinary wrench 110 will answer this purpose. It will be apparent that the ends of the shafts 56 and 52 should not extend beyond the outer periphery of the flange 44 so that the annular member 45—46 may slide over their ends 115 and cover them, when so desired. Other forms of valve mechanism may be used for letting the fuel into the hopper 48 of my device, when so desired.

In the lower part of the hopper 48 I provide a shaft 57 on which are secured a plurality of arms 58 so that when the shaft 57 is rotated, the arms 58 will pass through the fuel in the hopper and prevent such fuel from packing, and also facilitate the pas- 125 130

sage of the fuel downwardly through the discharge opening 59 of the hopper into the feeding mechanism.

The feeding mechanism comprises a cylinder 60 having a plurality of recesses 61 in its periphery and adapted, when the cylinder 60 is rotated, to receive fuel into the recesses or pockets 61 and carry such fuel down through the casing 62 from which it passes out through the narrow opening 63 in the bottom of the casing 62. The length of the opening 63 is substantially the same as the lengths of the recesses 61, but the width of the opening 63 is preferably very narrow so that the fuel falling downwardly out of the opening 63 will be a very thin sheet or curtain of fuel.

Air is preferably fed into one end of the casing 62 through a pipe 64 into a chamber 65. The cylinder 60 is preferably made up of two parts 60 and 60', see Fig. 10. The part 60 has the fuel recesses 61 therein, and the part 60' has chambers 66 extending the full lengths of the recesses 61. The chambers 66 are connected at their ends by passages 67 with the chamber 65 so that air may pass through the passages 67 into the chambers 66, and from thence through narrow slits 68 which extend the full lengths of the recesses 61. The parts 60 and 60' are preferably formed separately, and the members 60' fitted into the member 60 and may be adjusted so as to vary the widths of the slits 68, when so desired, so that in making up the cylinder 60-60' these slits 68 may be formed in the desired widths to suit the fuel which is to be used with the device. The air in passing into the chambers 66 will back up and be forced out through the slits 68 throughout the full lengths of the latter owing to the narrow widths of said slits. The purpose of this air being forced into the recesses 61 is to insure the fuel being forced out of said recesses at the proper time when they are brought down opposite the opening 63.

As a means for preventing the air to be continuously forced into all of the chambers 66 at the same time, I provide automatic valve mechanism for controlling the openings through the passages 67. An example of such valves is the provision of recesses 69 formed in the cylinder 60-60', and in each of the recesses 69 a ball or other body 70 is provided, which is adapted to completely close the lower end of the recess 69 and consequently cut off the passage of air through the openings 67. From Fig. 9 it will be apparent that the balls 70 will be in the bottoms of the recesses 69 throughout their travel, except a small portion of the rotation of the cylinder, and such balls will be in positions to uncover the openings 67 when the recesses 61, ready to deposit fuel into the opening 63, are opposite such opening. This

valve mechanism facilitates the saving of air and prevents the air entering the recesses 61 which are on the upper side of the cylinder and receiving fuel from the discharge 59 of the hopper 48. The cylinder 60-60' is provided with trunnions 71 mounted on ball bearings 71', and one of said trunnions 71 is connected through gears 72 with the shaft 57. Said shaft 57 may also be mounted on ball bearings 73, the ball bearings, of course, alleviating friction and minimizing the power required for operating the device. The gears 72 are preferably enclosed in a housing 74, and the other ends of the shaft 57 and cylinder 60 are sealed by plugs or closing members 75 in the housing covering the latter so as to prevent the waste and loss of fuel which might be blown out around said bearings. One of the trunnions of cylinder 60 is provided with a worm gear 76 which meshes with a worm 77, and the latter mounted on a shaft 78 which is journaled in bearings 79 on the frame of the device. The shaft 78 carries a beveled gear 80 meshing with a gear 81, and the latter connected with a gear 82 which meshes with a pinion 83 on the shaft 84' of a driving motor 84, which may be an electric motor, or any other kind of motor to provide power for operating the device. The agitating member 57-58 and the cylinder 60-60' are preferably connected to the motor in such a manner as to be rotated quite slowly, and the driving mechanism between the motor and such members may be varied to suit the different kinds of power it is desired to use. Also connected with the motor 84 is a blower, the casing of which is indicated at 85 in Fig. 2.

The blower is connected with a conducting casing or tube forming a passage 86, see Figs. 6 and 8, which passes under the opening 63 from the feeding mechanism. The cross-area of the passage 86 at the point 87 in Fig. 8 is preferably rectangular or square and provided with two doors 88 which are mounted on shafts 89 and formed in such sizes that when they are brought to their dotted line positions they will substantially close the passage 86, and when between the positions shown in their full and dotted lines they will limit the passage of air through said passage 86. The passage 86 from the point 87 to the discharge opening 63 is preferably widened laterally and made narrow vertically, as clearly indicated in Figs. 6 and 8, and at the point 90, immediately under the opening 63, has a rectangular cross section. The passage 86 after leaving the point 90 is preferably of substantially the same cross-area until it reaches the point 25 in the furnace, and the length of the passage between the points 90 and 25 is preferably such that the fuel and air has just sufficient time to become thor-

oughly intermingled, because if the passage is too long, the fuel will begin to settle out of the air toward the bottom of the passage, and if the passage is too short, the fuel will 5 not become thoroughly mixed with the air jet.

In the passage 86, just before reaching the point 90, I preferably provide a screen 91 of very fine mesh and mount this screen 10 in a manner so that it is slightly inclined, as clearly indicated in Fig. 8. The inclination of the screen 91 is preferably such that the air will be blown through the screen in such a manner as to be thoroughly mixed 15 with the fuel dropping from the opening 63. By inclining the screen 91, the air will be directed slightly downwardly after passing such screen and insure that parts of the fuel will be blown down to the bottom of the passage 20 in order to thoroughly mix the fuel with all of the air passing through the screen. Where the screen 91 is placed vertical, the air passing through the upper part 25 of the screen would take most of the fuel along with it, and the air passing through the bottom of the screen would get very little of the fuel, while in inclining the screen 91 to the proper degree, the fuel is distributed substantially equally to all of 30 the air passing through the screen.

The opening 63 is preferably provided with a movable member 92 which will move in a manner to increase the width of the opening 63, as clearly indicated in Fig. 8. 35 The screen 91 is carried by the member 92 so that the screen 91 always bears the same relation to the fuel falling through the opening 63.

The amount of fuel coming through the 40 opening 63 is therefore controlled by the member 92, and the latter is connected through the connecting mechanism 93 with the shafts 89 so that varying the width of the opening 63 moves the doors 88 to vary 45 the amount of air passed through the passage 86. Any desirable operating means, not shown, may be attached to a convenient portion of the connection 93, such as at opening 94, for moving the members 88 and 92.

50 It is sometimes desirable to see how much material there is in the hopper 48, I therefore provide a window 95 in a suitable position for viewing the interior thereof. In raising the barrel 11 from its full line position to its dotted line position, the barrel is inverted some time during such travel by swinging it on its pinions 27 so that when it reaches the dotted line position it is inverted and ready to be connected with the top of the 55 hopper 48. The ends of the cylinder 60 may be provided with annular gaskets 65 set in, as indicated, for facilitating the holding of the fuel away from the bearings of said cylinder.

65 While I have illustrated and described the

preferred form of my invention, I do not desire to be limited to the precise details set forth, but desire to avail myself of such variations and changes as come within the scope of the appended claims.

70

I claim:

1. The method of introducing fuel for burning in powdered form comprising dropping the fuel through a narrow opening into a space comparatively narrow vertically and 75 long laterally in a continuous thin sheet and forcing a current of air at a slight angle downwardly against one side of such sheet of fuel.

2. The method of introducing fuel for 80 burning in powdered form comprising feeding the fuel through a long narrow opening into a relatively shallow space in a continuous thin sheet or curtain and forcing a current of air divided into fine jets at acute angles against one side of the sheet or curtain 85 of fuel.

3. Apparatus for burning powdered fuel comprising a casing enclosing a passage substantially rectangular in cross-section relatively narrow one way and wide the other; means for feeding a thin sheet of fuel into said passage at substantially right angles to the length of the latter; means for directing air through said passage; and means directing said air against the fuel at an angle to the longitudinal median line of the passage. 90

4. Apparatus for burning powdered fuel comprising a substantially rectangular tube with a fuel opening in one side; means for feeding the fuel into said tube through said fuel opening in a thin sheet; means for varying the size of said fuel opening; a source of air supply connected with said tube; and means in said tube for controlling 100 the passage of air through said tube, said last-mentioned means being connected with the control means in said fuel opening for simultaneously controlling the supply of fuel and air into said tube. 110

5. Apparatus for burning powdered fuel comprising a tube having a portion substantially rectangular in cross-section and relatively narrow in one direction and wide in the other direction with a narrow slit extending substantially across one wide side thereof providing a fuel opening; means for feeding fuel through said fuel opening into and across the interior of said tube; a foraminous member extending across the interior of the tube adjacent said fuel opening; and a source of air supply connected with said tube and adapted to direct air through said member against the fuel as the latter is moved across the interior of the tube. 115

6. Apparatus for burning powdered fuel comprising a tube having a substantially uniform cross-section throughout a predetermined portion at its discharge end said cross-section being relatively shallow and wide; 120

130

walls enclosing a chamber increasing gradually in size from one end to the other, both ends of said chamber being open and the receiving end of substantially the size of 5 and in communication with the discharge end of said tube; means for feeding fuel laterally into said tube at a distance from the discharge end of the latter; means for forcing a current of air through said tube against 10 said fuel; and a screen across the interior of said tube for breaking said current of air up into fine jets just before such air engages the fuel.

7. Apparatus for burning powdered fuel 15 comprising a tube having a substantially uniform cross-section throughout a predetermined portion at its discharge end said cross-section being relatively shallow and wide; walls enclosing a chamber increasing gradually in size from one end to the other, both ends of said chamber being open and the receiving end of substantially the size of 20 and in communication with the discharge end of said tube; means for feeding fuel laterally into said tube at a distance from the discharge end of the latter; and a screen extending diagonally across the interior of the tube at a position adjacent where the fuel is introduced into said tube 25 30 and adapted to break the current of air up into fine jets before such air engages the fuel.

8. Apparatus for burning powdered fuel comprising a fire-box having an opening in 35 one lateral wall; an imperforate bottom wall inclined with its upper edge terminating in said opening, said bottom wall sealing the furnace against air entering through the lower portion of said furnace; an intermediate wall disposed at an acute angle to the bottom wall above the latter and having one edge terminating in said opening; vertical walls in said furnace connected with the lateral edges of said intermediate and 40 bottom walls and having edges terminating in said opening; a tube connected with the edges of said walls terminating in said opening; and means for introducing air and fuel into said tube and forcing such air and fuel 45 50 into said fire-box.

9. Apparatus for burning powdered fuel comprising a tube; means for forcing air into said tube; a fuel hopper adjacent the tube and in communication therewith; a 55 roller in said hopper having a plurality of longitudinal recesses in its periphery adapted to take fuel from the hopper and discharge such fuel into the tube; and means for supplying air to each of the recesses in 60 said roller for facilitating removing the fuel from said recesses and forcing such fuel into said tube.

10. Apparatus for burning powdered fuel 65 having a fire-box, a tube opening into said fire-box, means for feeding fuel to said tube

comprising a container and a supply hopper, an annular member adapted to be seated upon the top of the hopper and provided with a flange upon which the container may be supported in inverted position, means 70 for holding the annular member in place on the top of the hopper, means for clamping the container and annular member together, swinging members mounted on the annular member, and means for controlling the 75 position of the swinging member to permit material to be discharged from the container into the hopper, and means for supplying air under pressure to said tube to convey such fuel into the fire-box. 80

11. Apparatus for burning powdered fuel having a fire-box, a tube opening into said fire-box, means for feeding fuel to said tube comprising a container and a supply hopper, an annular member adapted to be seated upon the top of the hopper and provided with a flange upon which the container may be supported in inverted position, means for holding the annular member in place on top of the hopper, means for clamping the container and annular member together, swinging members mounted on the annular member, a shaft mounted in the annular member, connections between the swinging members and the shaft, locking means associated 90 with the shaft for permitting the swinging members to be held in any desired position, and means for supplying air under pressure to said tube to convey such fuel 95 into the fire-box. 100

12. Apparatus for burning powdered fuel comprising a tube; a fuel hopper connected with said tube; a feed roll in said hopper having longitudinal fuel recesses in its periphery and a longitudinal chamber extending along and in communication with each recess throughout the length of the latter; an air supply connected with said chambers; and means for controlling the supply of air to said chambers. 105

13. Apparatus for burning powdered fuel comprising a tube; a fuel hopper connected with said tube; a feed roll in said hopper having longitudinal recesses in its periphery and a longitudinal chamber extending along and in communication through a narrow opening throughout its length with each recess, there being a passage from the end of each chamber to the end of the roll; an air supply communicating with said passages, 115 and means in each passage for controlling the supply of air through such passage. 120

14. Apparatus for burning powdered fuel comprising a tube; a fuel hopper connected with said tube; a feed roll in said hopper 125 having longitudinal recesses in its periphery and a longitudinal chamber extending along and in communication through a narrow opening throughout its length with each recess, there being a passage from the end of 130

each chamber to the end of the roll and inclined recesses intersecting such passages; a ball valve in each of the last-mentioned recesses adapted to close the passage intersecting the recess in which said ball is located; and an air supply connected with said passages.

15. Apparatus for burning powdered fuel comprising a tube; a fuel hopper connected with said tube; a feed roll in said hopper having longitudinal fuel recesses in its periphery and a longitudinal chamber extending along and in communication through a narrow opening throughout its length with each recess, there being a passage from the end of each chamber to the end of the roll and recesses extending inwardly of the periphery of the roll and intersecting said passages; ball valves in said last-mentioned recesses, the latter being disposed to cause said balls to automatically close said passages at the side of the roll away from the tube and open said passages of the roll at the side of the latter adjacent the tube; and air supply means connected with said passages.

16. Apparatus for burning powdered fuel, comprising a substantially rectangular tube with a narrow fuel opening in one side, means for feeding the fuel into said tube through the fuel opening in a thin sheet, means in the fuel opening for varying the size of the opening, a source of air supply connected with the tube, means in the tube for controlling the passage of air therethrough, and means operatively connecting the means in the fuel opening and the controlling means for actuating the same in unison.

17. Apparatus for burning powdered fuel

comprising a tube having a fuel opening in one side; means for feeding fuel through the fuel opening into said tube; means for varying the width of said fuel opening; means for supplying air under pressure to said tube; doors hinged at opposite sides of and in said tube adapted to substantially close the interior of such tube; and a connection between the doors and the means for varying the width of the fuel opening adapted to simultaneously vary the width of said fuel opening and open and close said doors for varying the amounts of fuel and air admitted to said tube.

18. Apparatus for burning pulverized fuel, comprising a tube, a fuel hopper connected with said tube, a feed roll in said hopper having longitudinal recesses in its periphery and longitudinal chambers extending along and in communication with the recesses through narrow openings throughout their length, said roll being provided with passages extending from the ends of the chambers to the end of the roll and inclined recesses extending transversely to and intersecting the passages, means for supplying air through the passages to the chambers, and balls in the recesses adapted to cut off the supply of air through the passages as the recesses and chambers pass upwardly from a position underneath the hopper, and to permit air to enter the chambers to aid in discharging material from the recesses as these portions of the roll pass over the lower portion of their path.

In testimony whereof I have signed my name to this specification on this 10th day of May, A. D. 1918.

ALONZO G. KINYON.
